STRETCHING FRAME

Nicholas Landolphi, Danvers, Mass., assignor to
 A. C. Lawrence Leather Company, Peabody,
 Mass., a corporation of Maine

Application July 28, 1931, Serial No. 553,515

9 Claims. (Cl. 149—21)

The present invention relates to stretching frames for use with stretching machines for stretching hides, skins, or the like.

In the operation of such machines the work is first secured or mounted on the frame which is expanded by the machine to stretch the hide or skin. The frame is then locked or secured in expanded condition and removed from the machine for drying or other operation while so stretched, after which the frame is released or collapsed, the skin removed and the frame ready for a repetition of these operations.

The object of the present invention is to provide a stretching frame which will be strong and durable to resist the heavy strains and rough usage to which such apparatus is normally subjected, which may be quickly and positively secured in expanded position and released therefrom in a simple and expeditious manner, and which, when released or unlocked, will be prevented from excessive collapsing movement.

Other features of the invention consist of the construction and arrangement of parts herein-after described and claimed, the advantages of which will be obvious to those skilled in the art from the following description.

In the accompanying drawing, illustrating the invention in its preferred form, Fig. 1 is a plan view of a stretching frame having a hide supported therein; Fig. 2 is a plan view and Fig. 3 is a side view of one end of the lateral member of the frame with the bracket secured thereto; Fig. 4 is a similar plan view and Fig. 5 is a side view of one end of the longitudinal member with the plate mounted thereon; Fig. 6 is a plan view of a corner portion of the frame illustrating the bracket and plate in operative position; Fig. 7 is a sectional elevation taken on the line 7—7 of Fig. 6; and Fig. 8 is a side view of the locking pin which locks the bracket and plate together and holds the frame in its expanded stretching position.

The general construction of the frame is illustrated in Fig. 1, and comprises four members arranged in rectangular form with securing means at each corner to permit expanding and contracting relative movements of the members and to lock the frame rigidly in the desired position. The hide or skin is shown mounted in the frame, while the latter is collapsed or contracted, by means of clamps or "toggles" clipped to the marginal or edge portion of the skin with cords extending to and secured upon the members of the frame, sufficient tension being exerted upon the toggle ends in mounting the skin in the frame to insure its being held securely in flat and relatively smooth condition.

The frame members are conveniently constructed of wood of sufficient width and thickness to resist the strain incident to use. To protect

the corners from damage and to prevent excessive movement of the members when the frame is released or unlocked, and to provide a simple and convenient form of locking mechanism, cooperating brackets and plates are secured to the ends of the members. Thus the end members 10 carry the brackets 12 of proper dimensions to receive the ends of the longitudinal members 14. These brackets are attached firmly by means of screws 16 and nuts 18. By carrying the outer ends 20 of the brackets around the ends of the members, the latter are protected from jamming and splitting.

The ends of the longitudinal members 14 are received beneath these brackets 12, and these ends are provided with plates 22 having a down-turned outer end 24 to protect the end of the member, and an upturned inner end 26 in position to engage the side of bracket 12 and limit the inward movement of the end member 10 when the frame is released or unlocked. The plates are secured to their members by wood screws 28 and machine screws 30 and countersunk nuts 32.

The members are locked together by means of pins 34, as shown in Figs. 6 and 7, one at each corner, passing through registering holes in the plates and brackets. In order to permit the locking of the frame members together in substantially their exact relative position after the frame has been expanded by the stretching machine, the plates and brackets have been provided each with a series of holes or perforations 36 so arranged and spaced that within the range of stretching movement of the members, there will always be some hole in the plate in substantial register with some hole in the bracket ready to receive the locking pin 34. Thus, as shown, the perforations in both brackets and plates may be regularly arranged in a number of evenly spaced rows, and the spacing of the rows and of the perforations in each row may be made very slightly greater in the bracket than in the plate. At the most, only a slight tap of a light hammer or other tool will be required to drive the pin home, as illustrated in Fig. 7. In order to provide clearance for the end of the pin, the top surface of the longitudinal members may be recessed beneath the plate, as at 38 in Fig. 7.

In operation, the hide or skin is mounted in the frame or "toggled" with the frame in collapsed or contracted position, the locking pins having been entirely removed or inserted in the innermost holes. This toggling can be done directly on a stretching machine of the type shown in the pending application of Griffin & O'Neil, Serial No. 266,365, or on a separate table or support, being transferred to the machine for the stretching operation. With the pins removed, the machine will be set in operation to expand the frame

and when the desired amount or degree of stretch has been imparted to the skin, the machine is stopped and while it holds the frame expanded, the pins are set in the registering holes in bracket 5 and plate, thus positively locking the frame in its expanded position.

The machine is now set in reverse operation, releasing the frame from expansive pressure and permitting it to be removed for drying or treating 10 of the stretched skin. When this has been completed the frame may conveniently be unlocked and collapsed by placing it again on the stretching machine and exerting sufficient expansive pressure to permit withdrawal of the 15 pins, after which the machine is reversed, the frame collapsed or contracted, the toggle cords unfastened and the skins removed, leaving the frame ready for the toggling of another skin and a repetition of the process.

20. Inasmuch as these frames with the stretched skins thereon are ordinarily set on edge for drying or other operation, the ends of the plates and brackets overlying the ends of the wooden frame members serve as wear plates to protect the members from wear and damage. Since no substantial portion of the ends of the wooden members is removed, as is the case with prior constructions, the full maximum strength of these 25 portions of the members is obtained, and breakage at the points of connection is practically avoided. Furthermore, even when the locking pins are removed, collapsing movement of the frame beyond normal or toggling position is prevented by the upturned inner ends of the plate 30 and the inner walls of the brackets, thus avoiding the necessity of inserting the locking pins for 35 the toggling operation.

40. While in the accompanying drawing and foregoing description the preferred form of the present invention has been illustrated and described, it is to be understood that the invention may be embodied in other forms and arrangements.

45. Having thus described the invention, what is claimed is:

1. A stretching frame comprising a plurality of side members having overlapping end portions provided with cooperating perforated surfaces, the perforations being regularly spaced 50 and the spacing distance differing slightly in the two cooperating surfaces to bring one pair of perforations substantially in register, irrespective of the relative adjustment of the members.

55. 2. A stretching frame having, in combination, a plurality of side members having overlapping end portions, a perforated plate secured to the end portion of one member, and a bracket secured to the adjacent end portion of another member, the plate having its inner end upturned 60 to form a stop and the bracket having a perforated portion offset from the member to receive between such portion and member the plate and end portion of the other member, the perforated plate and perforated portion of the bracket being adapted to receive a locking device 65 in a perforation on each.

70. 3. A stretching frame having, in combination, a plurality of side members having overlapping end portions, a flat perforated plate secured to the top surface of one member with a down-turned flange overlying the end of such member, and a bracket secured to the top surface of the adjacent member having a perforated portion offset from the surface of such member and an 75 end portion overlying the end of said member,

the perforated plate and perforated portion of the bracket being adapted to receive a locking device in a perforation on each.

4. A stretching frame having, in combination, a plurality of side members having overlapping end portions, a flat perforated plate secured to the top surface of the end portion of one member, the plate having a downturned flange at one end overlying the end of the member, and an upturned flange at the other end to form a stop, a bracket secured to the end portion of the other member and having a downwardly and 80 backwardly turned portion to engage the end and the bottom surface of said member, and an offset portion parallel with and spaced from the top surface of the member to receive the end of the other member and its plate, the offset portion of the bracket and the plate being provided with a plurality of perforations to receive a locking pin to lock the members together. 85

90. 5. A stretching machine having, in combination, a plurality of side members having overlapping end portions, the top surface of the end portion of one member being recessed, a flat perforated plate secured to the top surface of said member over said recessed portion, and a perforated bracket secured to the end portion of the adjacent member, the perforated plate and the perforated bracket being adapted to receive a locking device in a perforation on each and the 95 recess to receive the projecting end of such device.

95. 6. A stretching frame having, in combination, a plurality of work holding members with overlapping end portions, certain of said members having a bracket secured thereto, the bracket comprising a perforated portion spaced from the top surface of the member, an outer end portion at right angles to the perforated portion to form an outer stop for the other member and extending over the end of the bracket-carrying member and turned inwardly for attachment to the bottom surface of said member, the inner end of the bracket being at right angles to the perforated portion to form an inner stop for the 110 other member and carrying a flange for attachment to the top surface of the bracket-carrying member. 115

120. 7. A bracket for stretching frames comprising a body portion, right angle supporting walls at the ends thereof, and right angle attaching flanges on the walls, the walls being of different height to offset the flanges, whereby the end of a frame member may be received between the flanges. 125

130. 8. A stretching frame comprising a plurality of side members having overlapping end portions, each provided with a multiplicity of rows of perforations adapted to receive locking devices in a perforation in each member, the perforations of each row being offset with respect to the perforations in the adjacent row, and the portions of the members intermediate the perforated end portions being imperforate. 135

140. 9. A stretching frame comprising a plurality of side members having overlapping end portions, each provided with a multiplicity of perforations, the perforations being of such number and so relatively arranged that a plurality of perforations of one member will overlap to a varying degree the perforations in the other member, and a single pair of perforations normally being in register one in each of the overlying members and adapted to receive a locking device. 145
